COMBINED CLOSURE AND APPLICATOR

Robert E. McCuiston, Greensboro, N. C., and Herman O. West, Narberth, Pa., assignors to Vick Chemical Company, New York, N. Y., a corporation of Delaware

Application October 22, 1940, Serial No. 362,288

2 Claims. (Cl. 221—148)

This invention relates to a combined closure and applicator of the general character used primarily, but not necessarily, for medicines such as are applied drop by drop to the nose and/or throat.

A primary object of this invention is the development of an improved combined closure and applicator of the type disclosed in Yates and DeLaney Patent 2,092,792, issued September 14, 1937, and the objects set forth in said patent also constitute objects of this invention.

An additional object is the provision of a closure of the character described adapted to hold a dropper tube in securely related assembly at all times.

Other objects will in part be obvious and in part be pointed out hereinafter.

The invention therefore consists in the combination of elements, arrangement of parts, and features of construction all as will be herein-after disclosed, and shown in the accompanying drawing, wherein:

Figure 1 is an enlarged view in central, vertical section showing the invention applied to a bottle or container; and

Figure 2 is a sectional view taken along the line 2—2 of Figure 1.

Referring specifically to the drawing wherein like reference characters designate like or similar parts, the invention essentially comprises a closure cap 10, a one piece rubber or other elastic element 11, and a dropper tube 12 carried by the latter, all constituting a unit adapted for application and removal to or from a bottle or container 13.

Cap 10 may be made of any suitable relatively rigid material, for instance, sheet metal, and has screw threads at 14, engaging corresponding screw threads at 15 on the neck of the bottle 13.

Cap 10 also has an upper wall 16 which has a central opening at 17 and which wall is upwardly and inwardly bulged by doming or curving the same as shown.

In constructing the metal cap 10, the top 16 thereof extends inwardly in a horizontal plane as at 18 and is then bulged or domed slightly upwardly as at 19, after which the wall or top 16 again extends inwardly in a horizontal plane as at 20.

The elastic body 11 is preferably made in a single piece and has a bulb 21 which extends through the opening 17 in cap 10 and a basal flange 22 extending outwardly and disposed under, and marginally engaging top wall 16. Bulb

21 also has slightly above basal flange 22, an exterior peripheral bulge or protuberance 23 which is engaged by the outer surface of the top or wall 16.

5 Interiorly of elastic member 11 there is formed a groove 24 bevelled as at 25 to provide an interior annular rib 26 spaced above exterior protuberance 23. The function of this rib 26 is two-fold. It serves to define the compressible limit 10 of the bulb 21 at its lower portion when said bulb is being used to fill the dropper tube 12 or expel the contents therefrom and plays a further part in the complete assembly as herein-after described.

15 Dropper tube 12 is provided with a bead or flange 27 adapted, when the device is assembled, to engage groove 24. The base of elastic device 11 is provided with an aperture 28 in communication with the interior of bulb 21, the 20 base portion of flange 22 being chamfered as at 29 adjacent aperture 28.

25 Dropper tube 12 has adjacent its upper extremity a circumferential groove 30 so positioned as to locate the bead or flange 27 at a height slightly less than that of groove 24.

In assembling the device a conventional assembly machine is utilized, comprised of a rotating disc in suitable apertures of which a plurality of the caps 10 are mechanically positioned, 30 base upward. Operators insert bulb elements 11 therein and as the disc is rotated mechanical means grip the bulb pulling the same into assembled position, with protuberance 23 seated on one side of the top wall 16 and flange 22 engaging the other side thereof. Dropper tubes 12 are next mechanically inserted through apertures 28, chamfer 29 serving as a centering guide, until bead 27 engages groove 24, whereupon the device now completely assembled in relatively 35 rigid fashion is discharged from the machine.

The invention is primarily utilized with a medicine contained within the glass or other bottle or receptacle 13. To this end the bulb 21 is compressed and released to draw the medicine 45 into the dropper tube 12 while the cap 10 is detached from the bottle 13. Further pressure on the bulb will then expel the medicine for application.

The construction is such that upon contraction of the bulb 21 for the purpose of drawing medicine into the dropper tube 12, the interior 50 annular rib 26 is forced downwardly against the bead 27 of the dropper tube 12 causing through the bevel 25 a stress in a downward direction to firmly retain the dropper tube 12 within the

groove 24. An additional stress is simultaneously produced by bending of the rubber member so that protuberance 23 exerts pressure in an opposite direction against the inner portion of horizontal plane 20 of the metal cap 16 at its point of contact and at the same time exerting inward stress to cause the wall of aperture 28 to compress very tightly about the enclosed portion, groove 30, of the dropper tube 12. It will be realized that a relatively wide double-ended compressing portion is produced at the base of the bulb which partakes of the combined thicknesses of the flanges 23 and 25 as well as that part of the wall of the bulb to which they are connected, and that such flanges and part are intersected by the inclined surface of a cone whose base is that of the body and whose apex is located above the flange 25. Such compression is aided by the chamfer 29. By this construction the elastic member 11 is caused to hold the dropper tube 12 more tightly during the operations of filling and discharging insuring against accidental disengagement of the tube from the rubber member when suction and pressure are present.

When the dropper is not being used the parts return to their normal position as shown in Figure 1 and the flange 22 by reason of its engagement with the upper edge of the bottle 18 forms an effective seal for the bottle to prevent the escape of the volatile constituents of the medicament contained in said bottle.

We claim:

1. In a closure, an elastic body provided with a hollow bulb, a bottle-neck sealing flange extending laterally and exteriorly at the base of said body having a central opening leading to the hollow of the bulb, a relatively narrow exterior lateral flange on the bulb above and close to said base, an attaching cap for the body having a portion extending between and retained by said flanges disposed for contact by the second flange when the bulb is compressed, a dropper tube fitted in said opening having a laterally extending bead at its top, said bulb having an interior annular groove at approximately the same distance above the base of the body

as the second flange and occupied by said bead, and an interior flange on the bulb above the planes of the first and second flanges engaging the upper surface of the bead, the bulb thereby having a relatively wide double-ended compression portion partaking of the combined thickness of the second and third flanges and that part of the wall of the bulb to which they are connected, said second and third flanges and said part being intersected by the inclined surface of a cone whose base is that of the body and whose apex is located above the third flange.

2. In a closure, a one piece elastic body provided with a hollow bulb, a bottle-neck sealing flange extending laterally and exteriorly at the base of said body having a central opening leading to the hollow of the bulb, a relatively narrow exterior lateral flange on the bulb above and close to said base, an attaching cap for the body having a portion extending between and retained by said flanges disposed for contact by the second flange when the bulb is compressed, a dropper tube fitted in said opening having a laterally extending bead at its top, said bulb having an interior annular groove at approximately the same distance above the base of the body as the second flange and occupied by said bead, and an interior flange on the bulb above the planes of the first and second flanges engaging the upper surface of the bead, said third flange being relatively narrow and beveled so that the second flange will coat with the bead under compression in retaining the dropper tube, said dropper tube having a shoulder spaced from said bead, the first flange around said opening being chamfered and fitted by said shoulder, the bulb due to the construction described having a relatively wide double-ended compression portion partaking of the combined thickness of the second and third flanges and that part of the wall of the bulb to which they are connected, said second and third flanges and said part being intersected by the inclined surface of a cone whose base is that of the body and whose apex is located above the third flange.
